US0D1058535S

(12) **United States Design Patent** (10) **Patent No.:** **US D1,058,535 S**
(45) **Date of Patent:** **** Jan. 21, 2025**

(54) **HEADPHONE**

(71) Applicant: **Shenzhen Huanfang Technology Co., Ltd.**, Shenzhen (CN)

(72) Inventor: **Huan Liao**, Shenzhen (CN)

(**) Term: **15 Years**

(21) Appl. No.: **29/963,825**

(22) Filed: **Sep. 19, 2024**

(51) **LOC (15) Cl.** **14-01**

(52) **U.S. Cl.**

USPC **D14/205**

(58) **Field of Classification Search**

USPC D14/205, 223; D24/174; 128/864-866;
381/380-381, 322, 328, 335; 362/105

Howard M. Cohn

(57) **CLAIM**

The ornamental design for a headphone as shown and described.

DESCRIPTION

FIG. 1 is a perspective view of a headphone showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

1 Claim, 8 Drawing Sheets
